UNITED STATES PATENT OFFICE.

CYRUS L. BUNDY, OF EAST ORANGE, NEW JERSEY, ASSIGNEE OF ONE-HALF TO WILLIAM BOHLEBER, OF NEW YORK, N. Y.

SPARK-PLUG.

1,212,449.

Specification of Letters Patent. Patented Jan. 16, 1917.

Application filed April 16, 1915. Serial No. 21,835.

To all whom it may concern:

Be it known that I, CYRUS L. BUNDY, a citizen of the United States, residing at East Orange, in the county of Essex and State of New Jersey, have invented certain new and useful Improvements in Spark-Plugs, of which the following is a full, clear, and exact description.

The invention which constitutes the subject matter of this application relates to a spark plug which is provided with means whereby the core can be quickly removed from the surrounding bushing for cleaning the electrodes, and for other purposes, without necessarily unscrewing the bushing from the engine.

In the drawings: Figure 1 is a side view of a full-sized plug showing the bayonet slot connection; Fig. 2 is a central longitudinal section of the plug; Fig. 3 is a section taken on line 3—3 of Fig. 1; Fig. 4 is a section on line 4—4 of Fig. 2.

Referring to the drawing in detail the reference numeral 10 designates a bushing of a spark plug provided with the usual screwthreaded lower end, and also provided with a bayonet slot 11. The character 12 designates the core, made of porcelain or other suitable material, and provided with suitable electrodes 13 and 14. At an intermediate portion the core is provided with a shoulder 15 which rests upon a corresponding shoulder 16 of the bushing 10. The core is provided with a sleeve 17 which is fixed against longitudinal movement by means of the shoulder 15 and a ring 18 of spring metal snapped into an annular groove encircling said core. The sleeve 17 however is fitted to freely rotate about the core. Preferably screwthreaded to the sleeve 17 is another sleeve 19 provided with laterally extending lugs 20 which are adapted to enter the bayonet slots 11 and when suitably turned are adapted to pass below and engage under the ears 21 of the bushing, the size and location of said ears being preferably as illustrated. The upper end of the sleeve 17 is provided with a handle 22 or other equivalent means for assembling and separating the core from the bushing.

The operation of the device is as follows: After the sleeve 17 has been properly positioned about the core and the sleeve 19 fitted thereon, as illustrated in Fig. 2, the lower end of the said sleeve 17 is shoul-

dered or spread as indicated at 23 so as to maintain the sleeve 19 in position thereon. It will therefore be seen that in rotating the sleeve 17 the sleeve 19, if held from rotation, has a limited vertical movement thereon—limited in the lower direction by the flange 23 and limited in its upward movement by the handle 22. It will therefore be seen that the core 12 is adapted to carry both electrodes and also the sleeves 17 and 19. As a result the plug is made up of two sections viz., the bushing and the core the latter of which also carries the securing means. In assembling the lugs 20 are caused to enter the bayonet slots 11 and are given a turn to the right which causes the lugs 20 to pass under the ears 21. The sleeve 19 being now prevented from upward movement, relative to the bushing 10, the continued rotation of sleeve 17 will cause the lower end 23 of the same to engage the shoulder 15 and force the same snugly upon the shoulder 16 of the bushing.

When it is desired to remove the core a reverse movement is imparted to the member 22. The parts should be so designed that a slight continued movement of the sleeve will cause a part thereof, in this case the shoulder or enlarged screwthread 23, to engage with the sleeve 19 and positively cause the latter to rotate and thus bring the lugs 20 from under the ears 21. This is preferably a jam engagement between the threads on the respective sleeves so that when the parts are again assembled there will be a sufficient frictional engagement to cause the lugs 20 to pass under the ears 21 and properly engage in the rear portion of the bayonet slot.

It is obvious that various changes in points of detail and other modifications may be resorted to without necessarily deviating from the true spirit and scope of my invention. I therefore do not limit myself to the specific construction shown and described.

What I claim is:

1. In a spark plug, a bushing provided with a bayonet slot in the upper portion thereof, a core, and means for securing the core within the bushing comprising relatively movable sleeves surrounding said core and screwthreaded to each other, one of which is provided with lugs adapted to engage the bushing within the bayonet slot.

and the other of which engages with the core for effecting a movement of the same relative to the bushing.

2. In a spark plug, a bushing provided with a bayonet slot in the upper portion thereof, a core, and means fixed to said core for securing the latter to the bushing comprising relatively movable sleeves one of which is provided with lugs adapted to engage the bayonet slot and the other of which is provided with a handle by which it is movable longitudinally with respect thereto.

3. In a spark plug, a bushing provided with a bayonet slot in the upper portion thereof, a core, and means fixed to said core for securing the latter to the bushing, comprising sleeves, the first of which is rotatable about but fixed against longitudinal movement on the core, and the second of which is screwthreaded to the first and provided with lugs adapted to engage the bayonet slot, and means on the first sleeve for rotating both of the sleeves to secure the core to and remove the same from the bushing.

4. In a spark plug, a bushing provided with a bayonet slot adjacent the upper end thereof and a shoulder at an intermediate

portion, a removable core for said bushing provided with a shoulder adapted to rest upon the shoulder of the bushing, and means carried by said core adapted to secure the same to the bushing comprising a member adapted to engage the bayonet slot and a rotatable member normally resting upon the shoulder of the core and coöperating with the aforesaid member to force the core downwardly into fluid tight engagement with the shoulder of the bushing.

5. In a spark plug, a bushing provided with a bayonet slot adjacent the upper end thereof and an annular shoulder at an intermediate point, a removable core for said bushing provided with a shoulder normally resting upon the shoulder of the bushing, and means carried by said core for securing the same to said bushing comprising a member engaging said slots and a second member engaging the first named member and movable longitudinally with respect thereto.

In testimony whereof I affix my signature in the presence of two subscribing witnesses.

CYRUS L. BUNDY.
